UNITED STATES PATENT OFFICE.

WILLIAM H. CLARK, OF CLEVELAND, OHIO.

APRON.

Application filed April 16, 1924. Serial No. 706,901.

To all whom it may concern:

Be it known that I, WILLIAM H. CLARK, a citizen of the United States, residing at Cleveland, in the county of Cuyahoga and 5 State of Ohio, have invented certain new and useful Improvements in Aprons, of which the following is a specification.

This invention relates to improvements in aprons and has for an object to provide a 10 structure wherein the several parts will at all times be snugly and comfortably fitted upon the body of a wearer.

Another object is to provide an apron of 15 this character in which the leg portions will cover a major portion of the wearer's legs.

It is likewise an object to provide an apron with a crotch portion and with means whereby the portion will at all times be retained in proper position regardless of the 20 movement of the wearer's legs.

Other objects will be in part obvious and in part pointed out hereinafter.

In order that the invention and its mode of operation may be readily understood by 25 persons skilled in the art, I have in the accompanying illustrative drawings, and in the following detailed description based thereon set out one possible embodiment of the same.

30 In these drawings:

Fig. 1 is a front elevation;

Fig. 2 is a vertical sectional view thereof.

Fig. 3 is a horizontal section showing the crotch engaging portion and

35 Fig. 4 is a view showing the extent to which the leg portions cover the wearer's legs.

This type of apron is well adapted for use by mechanics, automobilists etc. and 40 provides an apron which may be readily applied and which will reliably protect the front and sides of the wearer's clothing and in addition protect the portions of clothing between the legs at the crotch. At this 45 point it is desired to bring out that while somewhat similar designs of aprons are known to exist, they do not provide means for reliably protecting the clothing at the crotch of the wearer. In order to properly afford this protection, the portion designed 50 to afford the same, must be held against working forwardly and out of the crotch when the wearer is moving about. None of the types known by me, overcome this 55 objection.

Having more particular reference to the

drawings throughout which similar characters of reference designate similar parts this improved apron may be stated as comprising a body portion B made up of a single 60 piece of material or of complementary sections stitched together as at 5 and having pockets secured thereto. Leg portions 6 are included and are of sufficient area to cover not merely the front and sides of the legs 65 but in addition a part of the back portions thereof. As shown, the lower ends of the leg covering portions 6 are provided with adjustable straps which engage the legs of the wearer and retain the portions 6 in 70 proper relation to the legs.

The upper end or bib of the apron is provided with an adjustable neck strap 8 for supporting the apron. A waist strap 9 is attached at one end to one side of the 75 apron body portion and has at its other end a fastener 10 which fits over a button or the like 11 carried by the apron. Each of the straps heretofore referred to includes a structure as just outlined. 80

In order to provide protection for the clothing at the crotch of the wearer and insure this protection under all conditions, I so design the apron as to form an extension or crotch portion 12 which when 85 the apron is in use, assumes the position illustrated in Figures 2 and 3. In these figures it is seen that this crotch portion not only extends quite a distance through the crotch, but is provided with means 90 whereby it will maintain this relative position as regards to wearer's body. This means includes a connection between the rear end of the crotch portion and the waist strap 9, the connection being preferably in the form of what I term a crotch strap 13. This crotch strap 13 is stitched or otherwise secured at one end 14 to the crotch portion and is provided at its other end with a buckle 15 through the use of 95 which a loop 16 is formed for the reception of the waist strap 9 as shown. This loop is adjustable so as to vary the length of the strap 13 for use by persons of different sizes and proportions. Upon applying this apron to the body, the crotch strap 100 may be adjusted to the desired length to suit the particular individual wearing the apron and may thereby be rendered comfortable to him and at the same time function as intended. It is quite obvious that 105 as illustrated in Figure 2 there is no possi-

bility of exposing the crotch portion of the wearer's clothing to dirt etc.

Through adjustment of the neck strap and the crotch strap, this apron may be 5 quickly adjusted for use by different sized persons.

Certain changes in some of the minor details of construction may be resorted to and such changes as fall within the scope of 10 the appended claims, I consider within the spirit of my invention.

I claim:

1. An apron comprising a body portion having its lower end bifurcated to provide 15 leg portions, portions of the apron being arranged to extend through and cover a major part of the crotch of a wearer, a waist strap on the apron and means for directly connecting the crotch covering portion 20 and the waist strap to retain the crotch portion in snug engagement with the body of the wearer.

2. An apron comprising a body portion having its lower end bifurcated to provide 25 leg portions, portions of the apron being arranged to extend through and cover a major part of the crotch of the wearer, a waist strap on the apron and a crotch strap connecting the crotch covering portion and

the waist strap to retain the crotch portion 30 in snug engagement with the body of the wearer.

3. An apron comprising a body portion having its lower end bifurcated to provide leg portions, portions of the apron being arranged to extend through and cover a major part of the crotch of the wearer, a waist strap on the apron, a crotch strap secured at one end to the crotch portion and adjustable connection between the 40 waist strap and the crotch strap whereby to snugly engage the crotch portion with the body of a wearer.

4. An apron comprising a body portion having its lower end bifurcated to provide 45 leg portions, portions of the apron being arranged to extend through and cover a major part of the crotch of the wearer, an adjustable waist strap on the apron, a crotch strap secured at one end to the crotch portion and adjustable connection between the waist strap and the crotch strap whereby to snugly engage the crotch portion with the body of a wearer.

In testimony whereof, I affix my signature. 55

WILLIAM H. CLARK.
